UNITED STATES PATENT OFFICE.

JOSHUA S. McDANIEL, OF WICHITA FALLS, TEXAS.

BOTTLE-WASHING APPARATUS.

1,217,887.

Specification of Letters Patent. Patented Feb. 27, 1917.

Application filed April 29, 1916. Serial No. 94,311.

To all whom it may concern:

Be it known that I, JOSHUA S. McDANIEL, a citizen of the United States, residing at Wichita Falls, in the county of Wichita and 5 State of Texas, have invented certain new and useful Improvements in Bottle-Washing Apparatus, of which the following is a specification.

My invention relates to bottle washing 10 machines and particularly to devices which can be manually operated, and the object is to provide simple and inexpensive devices by which bottles can be quickly and efficiently washed clean with little effort on the 15 part of the operator and by which the bottles can be filled with and immersed in a hot caustic solution and then emptied and dumped into fresh water for rinsing. Other 20 objects and advantages will be fully explained in the following description and the invention will be more particularly pointed out in the claims.

Reference is had to the accompanying 25 drawings which form a part of this application.

Figure 1 is a side elevation of the bottle washing machine. Fig. 2 is a vertical longitudinal section of the same. Fig. 3 is a plan view of the same. Fig. 4 is a front elevation 30 of the bottle carrier.

Similar characters of reference are used to indicate the same parts throughout the several views.

This machine is provided with a tank 1 35 and this tank is divided into compartments A and B by a partition formed of two parts 2 and 3 which are spaced apart and form an air tight space 4 to prevent heat from passing from the compartment B to compartment A. A hot caustic solution is to be placed in the compartment B for soaking the 40 bottles. Fresh water is to be placed in compartment A for rinsing the bottles. Means are provided for placing the bottles in the 45 compartment B A consisting of hanger or bottle carrier 5. A bar 6 with a hole therethrough for an attaching rope or cable is secured to the top of the carrier 5. A rope or cable 7 is attached to the carrier and run over 50 a pulley 8 which is suspended from a beam 9 which is supported by an upright 10. The carrier 5 can be let down into and raised out of the hot solution as often as desirable and more than one carrier can be used if nec-

essary. When the carrier 5 is let down into 55 the hot solution in compartment B, the bottles will be filled with the solution.

Means are provided for emptying the bottles of the hot solution and dumping the bottles into the fresh water compartment. The 60 hanger or carrier 5 is drawn toward the partition and the bottle mouths will bear against the partition 2 when the hanger or carrier is brought into position to be elevated and thus be held within the carrier. A tilting 65 bar 11 is provided for tilting the bottles to empty the hot solution therefrom. As the carrier is raised, the mouths of the top layer 70 of bottles will strike the bar 11 and be brought to the position illustrated in Fig. 2. The bar 11 is pivotally connected to bars 12 and 13 by vertical pivots and the bar 13 has a handle 20 for swinging the bars 11, 12, and 13 in a horizontal plane on their pivotal connections. Bars 14 are attached to the upper 75 edges of the tank 1 by means of bars or blocks 15 which are attached to the sides of the tank. The bars 12 and 13 are pivotally connected to the bars 14 by vertical pivots 21 and the bars 12 and 13 will swing on the 80 pivots 21 as centers. By the means thus described the bar 11 can be swung back over the partition 2 so that the mouths of the top layer of bottles can pass above the bar 11. The bar 11 is then swung back under the 85 mouths of the bottles to catch the next layer of bottles. When the carrier is next raised, the second layer of bottles will be tilted in the same manner, as shown in Fig. 2. The tilting of the second row or layer of bottles 90 will make the second layer throw the first layer over the partition 2 and onto the chute or slide 16 so that the bottles will go mouth down into the fresh water in the compartment A. This operation is repeated until all 95 the bottles are emptied. The carrier 5 has a rack 17 on which the bottom layer of bottles is placed. The bottles are then stacked upon each other until the carrier is full. A float 18 may be formed on the bottom of the carrier 5 for aiding in lifting the carrier 5. The float will contain nothing but air, it being an 100 airtight closure.

Various changes in the sizes, proportions, and arrangements of the several parts may 105 be made without departing from my invention. The devices shown have been used to wash what are commonly called "soda

"water" bottles, but it is apparent that the devices can be used for washing other bottles, or vessels, such as milk bottles.

What I claim is,—

- 5 1. A bottle washing apparatus comprising a tank having a soaking compartment and fresh water compartment, devices for immersing bottles in said soaking compartment, means for elevating the immersing devices, and a shiftable bar coöoperating with said immersing devices for tilting the bottles for emptying the same and for dumping the bottles into said fresh water compartment.
- 10 2. A bottle washing apparatus comprising a tank having a fresh water compartment and a solution compartment, a partition between said compartments for preventing heat from passing from one compartment to the other, a carrier having one side open and adapted to receive superposed rows of bottles with their mouth ends projecting from said open side, means for suspending and vertically moving said carrier in the solution compartment, and a bar positioned 20 in the path of said vertical movement to tilt a row of bottles in such movement, and shiftable out of such position to permit the passage of said row above the bar, whereby successive rows of bottles may be first tilted to empty their contents into the solution compartment and then tilted to discharge the bottles into the fresh water compartment.
- 25 3. A bottle washing apparatus comprising a tank having a water compartment and a solution compartment, a carrier having provision for holding superposed layers of bottles, means for lowering and raising said carrier into and out of said solution, and a shiftable bar coöoperating with the carrier

for tilting said bottles for emptying their contents into the solution compartment and for dumping the bottles into said fresh water.

4. A bottle washing apparatus comprising a tank having a water compartment and a solution compartment, a partition inclosing a dead air space for preventing heat from passing from one compartment to the other, a carrier having provision for carrying layers of bottles superposed with their mouth ends projecting from one side thereof and having a float on the bottom part thereof, means for immersing said carrier with bottles therein into said solution, and a shiftable bar coöoperating with said carrier for tilting the bottles for emptying their contents into the solution compartment and for dumping the bottles into said fresh water compartment.

5. A bottle washing apparatus comprising a tank having a partition dividing said tank into fresh water and hot caustic solution compartments, a chute leading from said partition into the fresh water compartment, a carrier holding superposed layers of bottles with their mouth ends projecting from one side thereof and said partition coöperating with said carrier to prevent displacement of the bottles, means for lowering and raising said carrier into and out of said solution compartment, and a shifting bar pivotally connected with said tank for coöperating with said carrier to tilt the bottles to be emptied.

In testimony whereof, I set my hand this 20th day of April, 1916.

JOSHUA S. McDANIEL.
